United States Patent Office.

JAMES BARWICK, OF SILVERTOWN, NORTH WOOLWICH, ENGLAND.

Letters Patent No. 73,946, dated February 4, 1868.

IMPROVEMENT IN INKSTANDS.

The Schedule referred to in these Letters Patent and making part of the same.

TO WHOM IT MAY CONCERN:

Be it known that I, JAMES BARWICK, of Silvertown, North Woolwich, in the county of Essex, England, have invented certain new and useful Improvements in Inkstands; and I hereby declare the following to be a full, clear, and exact description of the same, reference being had to the accompanying drawings, in which—

Figure 1 is a vertical central section of an inkstand, constructed in accordance with my invention, and Figure 3 is a plan view of the same.

Figures 2 and 4 are like views of a modified form of my invention.

My invention relates to inkstands, in which the ink, when not in use, can be made to recede from the ink-cup into the reservoir, the object of such inkstands being, as is well known, to expose only a limited quantity of the ink, and that only when it is required to use the ink, to the action of the atmosphere, so as to prevent, as far as possible, the evaporating and thickening of the fluid.

To this effect I provide the ink-reservoir A, fig. 1, which may be made of hard rubber, glass, or other suitable material, with a cup, B, through the axis of which passes a hollow tube, C, closed at its upper end, and bearing on that portion which is received within the ink-reservoir a valve-plate, a, arranged to bear against the under side of the cup, so as to close the orifice or orifices in the bottom of the same. These orifices b, as shown in the drawings, are formed on opposite sides of the valve-tube, and open into the ink-reservoir. The closing of the orifices is effected by a tubular spring, D, of soft rubber or other suitable material, encircling the lower portion of the tube C, which, to this end, is made of considerably greater thickness, as is shown in the drawing, so as to fit snugly within the tubular spring. The lower end of the latter rests upon the bottom of the reservoir, and its upper end bears against the under side of the valve-plate a, in such manner as to hold it firmly against the valve-seat or under side of the ink-cup, so as to prevent the escape of the fluid which may be in the said cup. In order to more effectually close the orifices b, a washer, d, of soft rubber, or other suitable material, may be interposed between the valve-plate and seat.

When the ink-cup is filled, as shown in fig. 1, and it is desired to draw off the ink, the stem or tube C is pressed down so as to compress the tubular spring D, and separate the valve a from its seat, as shown in fig. 2. The ink now passes downwards through the orifices b, and between the valve and valve-seat, and returns to the reservoir, as represented plainly in the figure referred to. After all the ink has been drawn off, pressure is removed from the stem C, whereupon the spring D instantly forces the valve back into position, and the orifices b, are tightly closed, as before.

In order to fill the cup B, whenever it is desired to use the ink, I employ the following means: The reservoir is provided with a cup, E, which carries a bulb, F, of soft rubber, placed over an orifice, e, in the bottom of the cup, which communicates with the interior of the reservoir. In the top of the bulb (which has a dome-like form) is an opening, covered by a valve or plate, f, which is made in one piece with the rubber bulb. A series of apertures, g, is formed in the lower part of the rubber sleeve or spring, D, extending below the lower end of the valve-tube C; and in the upper end of the tube, at a point considerably above the bottom of the cup B, one or more holes, h, are made, through which the ink in the reservoir may be forced into the ink-cup.

The operation of this portion of the inkstand is as follows: When the cup B, which we will suppose to be empty, is to be filled with ink, the elastic bulb is pressed down by the finger, which is placed upon the valve f, so as to seal the opening in the top of the bulb, as shown in fig. 1. By this action, the air within the reservoir is compressed, and is caused to exert a pressure upon the fluid in the reservoir, which will force it through the aperture in the bottom of the tubular rubber spring, and up through the tube C, until it is discharged through the holes h, and falls into the cup. If one depression of the bulb does not suffice to force a sufficient quantity of ink into the cup, the finger is removed, so as to allow the bulb to spring back, and the valve f opens at the same time sufficiently to allow the air to enter and replace the fluid which has been forced into the cup. The operation is then repeated, and the "pumping" action continued until the requisite quantity of fluid has entered the cup. Generally two or three depressions of the bulb will be sufficient for the purpose.

In fig. 2 is shown a modified form of the inkstand. The "pumping" bulb in this instance is dispensed with, and an elastic ring, K, of rubber is employed. This rubber ring is "cured" to both the sides and the top m of the reservoir, which are thus united by an elastic and flexible connection. The rubber ring is so arranged

as to hold the top or cover *m* at some little distance above the sides of the reservoir, whereby the top may be depressed when occasion requires, and thus, like the bulb in fig. 1, force the ink up through the tube into the ink-cup. A perforation, *r*, in the top or cover, is covered by a valve or flap, *S*, the functions of the two being similar to those of the valve *f* and opening *e*, in fig. 1. In operating the cover so as to force the ink into the cup, the finger is placed over the valve *s*, so as to seal the opening *r*, and prevent the escape of the air. Other means may be also employed to produce this pumping action, as will be readily understood without further explanation.

The ink-reservoir, cup, and valve *F* prefer to make of hard rubber, and the elastic or flexible parts of soft rubber, as these substances not only can be formed so as to give a highly-ornamental appearance and finish to the inkstand, but also resist the action of the chemical ingredients which enter into the composition of ink or writing-fluid. Other suitable substances, however, may be employed, if desired.

Having now described my invention, and the manner in which the same is or may be carried into effect, what I claim, and desire to secure by Letters Patent, is—

1. The combination, with an ink-reservoir and cup, of a valve for holding and discharging the ink which the cup may contain, said valve being arranged within the reservoir, so as to close against the bottom or under side of the cup, substantially as herein shown and described.
2. The combination, with the ink-reservoir, dipping-cup, and valve, arranged as above described, of a valve rod, passing centrally or axially through the said cup, substantially as and for the purposes set forth.
3. The combination, with the ink-reservoir, cup, and valve, of a hollow, valve-operating stem, extending from within, and near the bottom of the reservoir, up through and above the bottom of the ink-cup, substantially as and for the purposes shown and described.
4. The combination, with the ink-reservoir, dipping-cup, and valve, of a rubber sleeve or other device for holding the valve against its seat with a yielding pressure, substantially in the manner herein shown and specified.
5. In an inkstand organized substantially as herein shown and described, I claim providing the valve-stem, when hollow, with discharge-openings, within the capacity of the ink-cup, and above the intended level of the ink held in the same, substantially as and for the purposes shown and specified.
6. The combination, with the closed ink-reservoir, the elastic bulb, or equivalent device for compressing the air within the same and the ink-cup, of a tube or conduit, opening from the reservoir into the cup at a point above the bottom of the latter, and a valve for holding and discharging the ink contained within the cup, substantially as and for the purposes shown and specified.

In testimony whereof, I have signed this specification before two subscribing witnesses.

JAMES BARWICK.
